UNITED STATES PATENT OFFICE.

VINCENT D. McDONNELL, OF CHICAGO, ILLINOIS.

GAS PRODUCER.

Application filed October 19, 1922. Serial No. 585,518.

My invention relates to an improved apparatus for producing a combustible gas from water and carbon adapted for heat or power generation. The invention contemplates the provision of an apparatus whereby a substantially continuous production of gas may be had and wherein a minimum quantity of air is admitted, which is automatically controlled for the purpose of controlling or regulating the temperature in the producer so as to produce a highly combustible gas.

Another object of my invention is to produce an apparatus wherein a regulable quantity of water will be admitted in a minute jet or stream and in such manner as to cause the water to be vaporized to such an extent as to be converted substantially into a dry steam, before it is admitted into the combustion chamber or fire-pot; my improved method providing a greater percentage of oxygen from the water used and enabling less use of free oxygen from air and therefore providing a product of low nitrogen content but of high hydrogen and other combustible content.

Another object of my invention is to provide means whereby the amount of water may be automatically controlled and its flow into the producer regulated or increased when the temperature in the apparatus exceeds a predetermined degree.

A further object of my invention is to provide means whereby the vaporized water will be admitted in a finely divided manner at a plurality of points into the bottom of the fire-pot and immediately beneath the mass of carbonaceous matter in order to compel the vaporized water to percolate through the incandescent zone of carbonaceous matter.

The objects and advantages of my invention will be more fully comprehended from the detailed description of the accompanying drawings, wherein:

Figure 1 is a side elevation of my improved apparatus with a portion of the walls or shells broken away and shown in section and the air and water admitting conduits with the control mechanism omitted.

Figure 2 is a vertical sectional view with a portion of the fuel magazine of the apparatus broken away.

Figure 3 is a vertical sectional view of a type of valve employed in the water and air-admitting lines or conduits.

Figure 4 is a cross sectional view taken substantially on the line 4-4 of Figure 2 looking in the direction of the arrows.

Figure 5 is a detail sectional view taken on the line 5-5 of Figure 4.

The apparatus, as disclosed in the drawings, comprises a preferably cylindrical shell or outer housing 10 of suitable dimensions and provided with a top or dome portion 11 which constitutes the fuel-receiving hopper or magazine having a fuel-introducing chute 12 adapted to be sealed against the admission of air by a suitable cover 13.

The outer shell or housing 10 is provided with an inner shell 14 of smaller dimensions to provide a chamber 15 disposed intermediate of the outer shell 10 and the inner shell 14 and extending circumferentially thereabout; the upper end of the inner shell 14 being open, while the lower end is provided with a bottom 16 disposed at a distance removed from the lower end of the outer shell 10. Mounted within the shell 14 and in spaced relation therewith is a third and open ended shell 17 of less length and width than the inner shell 14 so as to provide the spaced relation between the two shells 17 and 14. This inner shell 17 has an inner lining of suitable refractory material as at 18 throughout the entire length of the shell to constitute the fire-pot or generating portion of the producer; the refractory material 18 being supported in any suitable manner, as for example by an annular flange or ring 19 secured adjacent to the bottom of the shell 17. The upper end of shell 17 is flanged or provided with a ring 20 whereby the upper end of the chamber, intermediate of shells 17 and 14, is closed.

The shell 17 on its outer surface is provided with a spirally disposed trough 21 extending from a point adjacent the upper end of the shell 17 to the bottom thereof as shown in Figure 2. At the lower end of the inner shell 17 I provide a chambered ring 22 whereby the inner shell 17 is supported and a closure provided for the lower end of the chamber in which the spiral trough 21 is located; the ring 22 also constituting supporting means for the grate-bars 23. As shown in Figure 2, the ring 22 is provided with a plurality of ports or tuyères 24 extending therethrough for effecting communication between the chamber in which trough 21 is

located and the chamber beneath the grate-bars; the tuyères being arranged throughout the ring 22 except at the points where the ring is socketed to receive the extensions or trunnions of the various grate-bars 23. The grate-bars are oscillatably mounted in the annular member 22 in order that the respective grate-bars may be rotated when it is desired to clean out the fire-pot or to agitate the carbonaceous mass supported thereby. The main or body portions of the grate-bars 23 are chambered longitudinally as shown at 25 in Figures 4 and 5 and the body portions, intermediate of the laterally disposed ribs or prong portions 26 of the grate-bar, are provided with outlet ports or openings 27, see Figures 4 and 5. The extensions or trunnions of the different grate-bars 23 at one side are hollow or chambered and disposed through the walls or shells 14 and 10 to the exterior of the generator, where the outer ends are connected with a suitable manifold 28, with which the outer ends of the hollow trunnions communicate by means of a suitable number of ports 29; the immediate ends of the trunnions or extensions being closed in any suitable manner as for example by the plugs 30. The extensions or trunnions of the respective grate-bars 23 are also rotatably mounted in the manifold 28; the junctures between the grate-bars and the side walls or shells 14 and 10 and between the bars and the manifold being suitably seated against the inflow of air. The manifold 28 is provided with a conduit 31 which leads from a suitable source of air supply; the conduit being provided with a shut-off valve as at 32.

The upper end of the shell 10 is provided with a suitable lining or cast iron ring, as indicated at 33 which rests on a suitable flange or ring 34, secured on the inner side of shell 10, and also on the inner shell 14 and the lining of refractory material 18 of the fire pot. The lining 33 is shown tapered in Figure 2, to provide a suitable hopper for the fuel which will direct the fuel into the fire pot proper throughout its entire area. The lining 33 is shown provided with a depending portion or flange 33a adapted to extend slightly beneath the upper end of the refractory lining 18 but in slight spaced relation therewith so as to provide a small annular passage 35 leading from the upper end of the fire-pot; and the lining 33 at suitable intervals is provided with a suitable number of transversely disposed passages 36 each connecting at one end with the annular passage 35 whereby communication between the upper end of the fire-pot or generating chamber and the chamber 15, intermediate of shells 10 and 14, is effected.

Extending through shells or walls 10 and 14, in airtight relation therewith, at a point adjacent the upper end of the inner or fire-

pot shell 17, namely at a point above the upper end of the spirally disposed trough 21, I provide a conduit 37 which is adapted to communicate with a suitable source of water supply; the conduit 37 being provided at 70 a suitable point with a manually controlled shut-off valve 38.

The outer shell 10 is preferably provided with a bottom 39 arranged in spaced relation with the bottom 16 of shell 14 to provide a chamber therebetween, which is provided with a conduit 40 leading preferably from a central point in the chamber to the exterior of the outer shell 10. The inner end of conduit 40 is preferably closed as shown at 80 41 while the upper side, adjacent the end, is provided with an opening 42. The conduit 40 constitutes the outlet for the generated gas and by reason of its inlet end construction the generated gas must flow toward the center of the chamber and adjacent to the bottom 16 of inner shell 14, thereby enabling any dust or ash particles carried by the gas to be precipitated before the gas reaches inlet 42 of the conduit 40 which conveys the 85 gas to the point of use or storage; the construction at the same time provides an even exhausting or "pulling" action throughout the generator and thereby providing uniform incandescence throughout the fire-pot. 90

The air introducing conduit 31, at a point intermediate of the shut-off valve 32 and the manifold 28, is provided with a control valve 43 which is preferably of the construction shown in Figure 3 and provided with the diaphragm 44 whereby the inlet and outlet ends of the valve-casing are separated and this diaphragm in turn is provided with a port controlled by a disc valve 45, whose stem extends to the exterior of the valve casing and is provided with a lever 46 pivotally secured thereto. The shell or casing of the valve is shown provided with a yoke or bracket 47 to which the lever 46 is fulcrumed at 48; one end of the lever is provided with a suitable spring at 49 which is also secured to the lower end of the yoke or fulcrum forming bracket 47. With this construction it is apparent that the spring 49 will constantly exert a pulling force on lever 46 in a 105 direction away from valve 43 and therefore in a direction which will cause the disc-valve 45 to be normally held on its seat in the diaphragm 44 and therefore normally closing off communication with the conduit 31. The upper end of the lever 46 is formed to be attracted by an electromagnet 50 arranged in an electric circuit indicated at 51 when the circuit is closed and the magnet energized. This circuit involves a pyrometer of a well known construction, indicated at 52, and provided with an oscillatably mounted and magnetically controlled pointer or needle 53, which is adapted to close the circuit 51 when moved into contact with one 110 115 120 125 130

of the contact points 54, through the circuit induced by the thermo-couple 55 which extends into the chamber in which the spirally wound trough 21 is located.

- 5 The water-admitting conduit 37, intermediate of the shut-off valve 38 and the point of communication with the chamber in which the spiral trough 21 is located, is also provided with a control valve 43 whose 70
10 spring controlled lever 46 is adapted to be attracted by an electromagnet 56 arranged in circuit with the pyrometer previously referred to; that is to say the magnet 56 is adapted to be energized when the needle 53 is 75
15 moves into contact with one of the contact points 54. The valve 43, in the air conduit 31, is normally closed, while the valve 43 in the water line 37 is normally slightly open so as to constantly admit a minute, predetermined quantity or stream of water.

In order to compensate for unequal expansion and contraction between the refractory lining 18 and the metallic wall or shell 17 I mount the refractory lining 18 in slight spaced relation with the shell 17 and fill the intervening space with a suitable granular substance 18 which is not a heat insulator, as for example sand, whereby the heat will be conducted to the shell 17, in order to prevent 80
20 the vapor, which passes through tuyères 24, from passing upward between the lining 18 and the shell 17 and mixing with the gas at the upper end of the fire-pot.

- In operating the apparatus to carry out 35 my improved method, the carbon fuel, to-wit: charcoal or other suitable carbonaceous matter, is introduced into the magazine or hopper through the chute or inlet 13 and discharged onto the grate of the fire-pot. 100
40 The fuel is then ignited in the fire-pot, while at the same time both valves in the air supply line are opened to permit a sufficient amount of air to be formed through conduit 31, manifold 28, into the respective hollow 105
45 bars of the grate from whence it is discharged by the plurality of minute ports or openings 27 in the different grate-bars. This free admission of air is continued until the fuel and walls of the fire-pot are brought to 110
50 an incandescent heat, at which time shut-off valve 38 in the water supply line is opened to admit water into conduit 37. The control valve 43 in the water supply line is normally set to admit a predetermined minute quantity 115
55 of water into the conduit 37 in order that a small jet or stream of water will be continuously discharged into the upper end or turn of the spiral trough 21. 120
60 It is apparent that the lower fire-pot end of the inner shell or cylinder will be at a greater heat than the upper end, and as a result the minute quantity of water flowing slowly downward through the spiral trough, in intimate relation with the inner wall or 125
65 shell 17, will be gradually and progressively subjected to an increasing temperature which will cause it to be vaporized and brought to a substantially dry state, namely substantially convert it into superheated steam, before it is admitted into the bottom of the fire-pot beneath the incandescently heated carbonaceous mass; the vapor being evenly distributed throughout the bottom of the grate, so that complete gasification will take place instantly upon contact with and during passage through the incandescent carbon. 70
75

After initial generation, namely after the mass has been brought to an incandescent temperature, the valve 43 in air line 31 is released so as to close through the action of its spring 49, and combustion maintained mainly through the oxygen derived from the water, thus providing a gas high in hydrogen or other combustible content and comparatively free of a high nitrogen content which would result if air was freely and continuously admitted.

By reason of the grate-bar construction and method of introducing the air, the carbonaceous mass will be quickly brought up to incandescence, as the air is evenly distributed throughout the entire base of the fire-pot by means of the small ports 27 arranged in the longitudinal or body portions of the bars.

With the pyrometer control of the air supply and water supply lines, namely with electro-magnets controlling the two valves 43 and arranged in circuits established when indicator or needle 53 contacts with either of the terminals or contact points 54, 54, it is possible to maintain substantially continuous generation of gas as long as a sufficient supply of unconsumed carbonaceous material is in the generator. The thermo-couple 55, arranged in the vapor generating chamber, is intended to cause needle 53 to move into contact with one of the terminals or contact points 54 when the temperature in said chamber drops below a predetermined degree and to contact with the other terminal 54 when the temperature exceeds a predetermined degree; the needle causing an electric circuit to be established whereby either electro-magnet 50 or magnet 56 becomes energized. For example, if the temperature in the vaporizing chamber (namely the chamber in which spiral trough 21 is located) drops below a predetermined degree the thermo-couple 55 will induce needle 53 to swing to the left in Figure 2 and thereby establish a circuit whereby electro-magnet 50 becomes energized so as to attract the end of lever 46, of the control valve 43 in the air supply line, and cause the valve 43 to be opened to allow air to pass through conduit 31 and into the fire-pot through the ports in the grate-bars. This admission of a small quantity of air will increase the combustion and bring the temperature up to the desired 130
135

degree, when the circuit will be broken or opened, thereby allowing the spring 49 to close the valve in the air-line.

On the other hand, if the temperature in the vaporizing chamber exceeds a predetermined degree, needle 53 will be caused to move to the right in Figure 2 and complete a circuit whereby electro-magnet 56 becomes energized; thereby attracting the lever 46 of control valve 43 in the water supply line, with the result that this valve will be opened beyond its normal setting, thereby permitting a greater flow of water to enter the vaporizing chamber. This condition will maintain until the temperature drops back to the desired degree, when the circuit will be broken and the spring 49 of the control valve 43 in the water-supply line 37 will move the valve back to its normal position (namely slightly open) so as to diminish the admitted water to its normal flow.

In practice, I have found, in order to produce a suitable combustible gas, that the area of the vaporizing chamber, determined by the height of the fire-pot, and the grate area should be proportional or of a ratio within a certain range; that is to say, the area of the vaporizing chamber should be between six and a half to ten times the area of the grate. If the ratio between the total area of the vaporizing chamber and the area of the grate is less than the minimum proportions above given, the vapor will not be brought to a proper temperature and as a result the steam discharging into the fire-pot will be at a temperature which soon cools the incandescent carbon below the temperature for producing methane, hydrogen and a carbon monoxide. On the other hand, if too great a difference between the areas is provided, whereby the vapor is caused to have an extreme length of travel, the carbon monoxide will be converted into an inert gas and improper operation of the generator results.

The gas produced in the fire-pot rises to the upper end thereof and passes through the channels 36 into chamber 15 disposed about the shell 14 which constitutes one wall of the vaporizing chamber; the gas tending to heat the wall or shell 14 and therefore the vaporizing chamber, with the result that the temperature of the out-going gas is reduced.

I have shown and described an apparatus adapted to carry out my method of gas production, but modifications may be made without, however, departing from the spirit of my invention.

60 What I claim is:

1. In a gas producer, an air-tight generating chamber provided with a grate in the lower end thereof, a closed water vaporizing chamber disposed about the generating chamber and to be heated thereby, means lo-

cated in the vaporizing chamber whereby the incoming water will be caused to flow about the wall of the generating chamber from the upper to the lower end thereof, a chamber disposed beneath the grate of the generating chamber, means whereby communication between the vaporizing chamber and said last mentioned chamber is effected and the steam vapor delivered to said last chamber in small jets, a gas-receiving chamber arranged about said vaporizing chamber and beneath said third mentioned chamber so as to convey the heat of the gas to said chambers, regulable means for introducing water into the upper end of the vaporizing chamber, means whereby air may be conveyed through the grate into the generating chamber, and means controlled by the temperature in the vaporizing chamber whereby air is admitted when the temperature falls below a predetermined degree and an increased flow of water provided when the temperature exceeds a predetermined degree.

2. In a gas producer, an air-tight generating chamber, a closed water vaporizing chamber disposed about the generating chamber from top to bottom and to be heated thereby, said vaporizing chamber on its bottom being provided with a plurality of tuyères whereby the steam vapor is conveyed beneath the grate of the generating chamber, a gas-receiving chamber disposed about and lengthwise of the vaporizing chamber so as to convey heat thereto and having communication at its upper end with the upper end of the generating chamber, automatic regulable water introducing means communicating with the upper end of the vaporizing chamber, regulable air-introducing means communicating with the bottom of the generating chamber, and means controlled by the temperature in the vaporizing chamber adapted to affect the water-introducing means and the air-introducing means, whereby an increased flow of water is admitted into the vaporizing chamber when the temperature exceeds a predetermined degree and air is admitted into the generating chamber when the temperature falls below a predetermined degree.

3. In a gas producer, a generating chamber provided with a grate in the lower end thereof, a closed water vaporizing chamber, disposed about the generating chamber from top to bottom, having a total area of predetermined proportions relative to the area of the grate, means whereby the steam vapor from said vaporizing chamber is uniformly discharged in minute jets beneath the grate, a gas-receiving chamber having communication across the top of the vaporizing chamber with the upper end of the generating chamber and disposed about and throughout the length of the vaporizing chamber, and automatic means controlled by the tempera-

ture in the vaporizing chamber, whereby air is admitted to the bottom of the generating chamber when the temperature falls below a predetermined degree and an increased flow of water is admitted to the vaporizing chamber when the temperature rises above a predetermined degree.

4. In a gas producer, a generating chamber, provided with a grate having hollow trunnions communicating with the chamber exterior and provided with discharge ports in the bars of the grate, controllable air-admitting means communicating with said hollow trunnions, a water vaporizing chamber disposed about the generating chamber, regulable water-conveying means communicating with said vaporizing chamber, means whereby the steam vapor is discharged in minute quantities in the lower end of the generating chamber, and means controlled by the temperature in the vaporizing chamber whereby air is permitted to flow through the air-admitting means when said temperature falls below a predetermined degree and an increased flow of water through the water-conveying means permitted when said temperature exceeds a predetermined degree.

5. In a gas producer of the character described, a generating chamber provided with a grate in the lower end thereof, the bars of the grate being provided with air passages, regulable means whereby air may be admitted to said passages, a water vaporizing chamber disposed about said generating chamber and communicating with the latter at the bottom thereof, means whereby a regulable quantity of water is admitted to said vaporizing chamber, a gas-receiving chamber disposed about the vaporizing chamber and communicating with the upper end of the generating chamber and terminating at the bottom in a precipitating chamber, and gas outlet means disposed centrally within said precipitating chamber.

6. In a gas producer of the character described, a generating chamber provided with a grate in the bottom thereof, a water vaporizing chamber disposed about the generating chamber from top to bottom, regulable means whereby a continuous flow of water in a minute stream or jet is admitted into the upper end of the vaporizing chamber, means whereby the steam vapor from said vaporizing chamber is discharged in a plurality of small jets into the bottom of

the generating chamber, automatically controlled means whereby air may be intermittently admitted to the bottom of the generating chamber, a gas-receiving chamber disposed about the vaporizing chamber and beneath the generating chamber, said chamber communicating at its top with the upper end of the generating chamber and terminating at the bottom in a precipitating portion, and gas outlets means extending centrally from the precipitating portion of said gas-receiving chamber.

7. In a gas producer, a water vaporizing chamber, a generating chamber provided with a grate in the lower end thereof, the bars of the grate having air passages extending lengthwise thereof and laterally disposed discharge ports, the ends of the bars being extended through the walls of the generating chamber, a manifold in which the ends of the bars are rotatably secured, an air line connected with said manifold, and automatic means controlled by the temperature within the vaporizing chamber of the producer whereby the admission of air to said manifold is controlled.

8. In a gas producer, a generating chamber provided with a grate in the lower end thereof, the bars of the grate having air passages extending lengthwise thereof and laterally disposed discharge ports, the ends of the bars being extended through the walls of the generating chamber, a manifold in which the ends of the bars are rotatably secured, an air line connected with said manifold, a water vaporizing chamber disposed about the generating chamber and extending from top to bottom, said vaporizing chamber communicating with the generating chamber through a plurality of spaced ports opening beneath the grate, a spiral trough in the vaporizing chamber disposed about the wall of the generating chamber, means whereby a minute quantity of water is admitted to said trough, a gas-receiving chamber disposed about the vaporizing chamber, and automatic means controlled by the temperature in the vaporizing chamber whereby air is admitted to said manifold when the temperature in the vaporizing chamber falls below a predetermined degree and an increased quantity of water is admitted into the trough of the vaporizing chamber when the temperature of said chamber exceeds a predetermined degree.

VINCENT D. McDONNELL.
